UNITED STATES PATENT OFFICE.

JOHN B. RETALLACK, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 21, 1923. Serial No. 676,023.

To all whom it may concern:

Be it known that I, JOHN B. RETALLACK, a citizen of the United States of America, residing at East Orange, in the county of 5 Essex, State of New Jersey, have invented certain new and useful Improvements in Telephone-Exchange Systems, of which the following is a full, clear, concise, and exact description.

10 The present invention relates to telephone systems, and particularly, to systems employing automatic switches for the establishment of connections.

In telephone systems where connections 15 are established automatically, it is particularly necessary that all the apparatus be kept in the best possible adjustment at all times. This is true of the relays employed as well as of the switches themselves. In a manual 20 system the testing of relays is a comparatively simple matter, but in machine switching systems, the adjusting of the apparatus, to bring it into such a condition that the desired relays may be tested, is a problem 25 in itself.

In a system of the well-known power driven type such as is disclosed in U. S. Patent 1,504,261 granted to E. H. Mills, August 12, 1924, in order to test the so-called 30 supervisory relays, it is necessary to position the sequence switch which controls the operation of the secondary or district selector in a definite position. In the case of such selectors which serve subscribers who 35 are charged on a flat rate basis, the connection of a dial to the selector and the positioning of that selector is not very difficult. However, in the case of selectors serving subscribers' lines equipped with coin boxes, 40 the connection is not completed and the supervisory relay connected into the circuit until after a coin has been deposited.

It is, therefore, an object of the present 45 invention to provide simple and efficient means, in a testing arrangement for such a selector, to simulate the action of a coin for the purpose of advancing the district selector sequence switch into the desired position. A feature of the invention lies in 50 the provision of a relay of the correct resistance to imitate the coin box polarized relay and coin to advance the district selector sequence switch to talking position.

A further feature of the invention lies 55 in means for operatively connecting said

relay to the test circuit under the control of an operator.

Another feature of the invention lies in means for releasing the coin simulating apparatus by means of the coin collect or coin 60 refund current supplied through the selector under test.

A still further feature of the invention lies in the provision of a signal which is displayed when the attendant operates the coin 65 simulating means and remains displayed until said means is released.

These and other features of the invention 70 will be more clearly understood from a consideration of the following description 75 in connection with the drawings and the appended claims.

This invention has been embodied in a disclosure like that shown in the above 80 mentioned patent to E. H. Mills. In fact, in order to simplify the drawings and description, two figures of the drawing are 85 practically exact copies of two figures of the Mills patent. In the drawings, Fig. 1 shows a test line embodying the present invention, Fig. 2 shows a district selector and Fig. 3 a portion of a sender. Fig. 4 shows the manner in which Figs. 1 to 3 are to be arranged. Fig. 2 differs from Fig. 2 of the Mills patent only in the addition of jack 290. The 90 various parts of the drawing bear the same numbers as the similar parts of the Mills drawing. Fig. 3 differs from Fig. 12 of the Mills patent only in the addition of relays 647, 719, 630, 626, and 1302 with 95 their associated contacts and conductors. These relays perform the same functions as the correspondingly numbered relays in the Mills patent. Since the Mills patent describes in detail the operation of the system 95 as a whole, reference is made to that patent for the portions of the operation not completely traced in the present application.

For the purpose of testing district 100 selectors a test line 100 is provided which is 100 equipped with a dial 102 for causing the district selector to be positioned and with a pair of plugs 103 and 104 for connecting the district selector to the relay test box 101.

The trunk conductors terminating in district 105 selector switch 250 appear in multiple in the banks of a plurality of line switches and also in jack 290 which may be mounted in any convenient position.

When a district selector is to be tested, 110

plug 103 is inserted in jack 290 and key 105 is operated. This key 105 is a locking key and remains operated until released. The insertion of the plug in the jack immediately grounds conductor 291, thus rendering the district selector non-selectable. As soon as the key 105 is operated a circuit is completed from ground, resistance 106, upper contact of key 105, conductor 107, sleeve of plug 103, sleeve of jack 290, lower right contact of sequence switch cam 203, left normal contact of relay 227, left winding of sleeve relay 226 to battery in which circuit relay 226 operates.

15 Following the energization of relay 226, sequence switch 200 is advanced into position 2 and a sender is associated with the district selector. The operator then manipulates his dial to set up a registration on the sender corresponding to a number which may be one reserved for such tests. The sender is now operated and the district selector positioned. When the district selector has been positioned, sequence switch 200 is in position 9. In this position relay 261 is energized from ground in the sender and in energizing operates relay 228, which in turn, advances the sequence switch to position 10, in which position the sequence switch remains during subsequent selections. In the meantime, monitoring time measure switch M, shown in Fig. 3, has been operated, due to the operation of relay 626. When the time measure switch M passes 30 through positions 9 and 10, relay 1200 is operated. Since relays 1209 and 1216 have already been operated, a circuit is now completed to test whether a coin has been deposited.

40 In the test line 100 the operation of key 109 represents the deposit of a coin in a coin box and closes a circuit for relay 110 extending from battery, winding of that relay, closed contacts of key 109 to ground at the back contact of relay 111. Relay 110 operates and locks through its inner right front contact direct to the ground on the back contact of relay 111. Relay 110 also closes an obvious circuit for lamp 112 which indicates that the coin deposit simulating apparatus has been operated. At its outer right front contact, relay 110 connects ground through the winding of relay 111 and the upper contact of key 108 to the tip 45 of plug 103 and thence to the tip conductor of the district selector. At its inner left front contact, relay 110 connects ground to the sleeve of plug 103 to hold the sleeve relay operated after the key 105 has been released. Key 109 may be operated either before the operation of the dial 102 or immediately thereafter.

45 The previously mentioned test circuit extends from source 1260 of negative current through the left front contact of relay 1229,

the inner right back contact of relay 1212, the outer right back contact of relay 1215, the left windings of differential relays 1214 and 1231, bank terminals Nos. 9, 10 and 11 to which wiper 1206 has access, wiper 1206, 70 the outer front right contact of relay 1200, the outer right back contact of relay 1201, conductor 1202, left front contact of relay 630, conductor 636, wiper 232 of the sender finder SF, outer left front contact of relay 230, conductor 233, lower left contact of cam 212, tip of jack 290, tip of plug 103, upper normal contact of key 108, lower closed contact of key 105, through the dial 80 102, lower normal contact of key 108, ring of plug 103, ring of jack 290, lower left contact of cam 213, conductor 235, inner left front contact of relay 230, wiper 236, right front contact of relay 630, outer left back contact of relay 1201, outer left front contact of relay 1200, wiper 1233 and the ninth, tenth and eleventh contacts to which it has access through the right windings of relays 1231 and 1214, inner left back contact 85 of relay 1215, to ground at the outer right contact of relay 1205. Relays 1214 and 1231 being differentially and marginally wound do not energize in this circuit. However, if at this time key 109 has been closed and relay 111 connected to the tip conductor, an effective energizing circuit for relay 1214 is established, which is the same as that previously traced as far as the tip of plug 103 and upper contact of relay 108, and then extends through the winding of relay 111 to ground at the front contact of relay 110. Relay 1214 energizes in series with the winding of relay 111, but relay 1231 being marginally wound does not energize and relay 111 does not receive sufficient current 90 through the windings of relays 1214 and 1231 to energize at this time. The operation of relay 1214 opens the locking circuit of relay 1209, releasing relay 1216, which in turn opens the circuit of relay 647 and permits the completion of final units selection as disclosed in the above referred to Patent 1,504,261 to E. H. Mills. Relay 647 serves to open the fundamental circuit through stepping relay 719 of the sender when the sender is in position to control final units selection and prevents the completion of a connection until a coin has been deposited; or, in this case, until key 109 is closed.

100 On the completion of the selecting operations, the current through relay 261, at whose front contact relay 228 has been held energized, is reduced so that relay 261 releases, in turn releasing relay 228 which advances sequence switch 200 into position 11. In position 11 a new fundamental circuit is closed for controlling the advance of the sequence switch into the desired talking position, after which the sender is released.

When the district selector has been positioned in the talking position corresponding to the registration set up on the sender, supervisory relay 234 is connected through 5 the upper right contact of cam 213 and the lower left winding of repeating coil 265 to battery. Plug 104 may now be inserted in relay test box 101, key 108 operated, and any desired test made upon relay 234. 10 This test box may, for example, be of the type set forth in U. S. Patent 1,236,491 to B. H. Skinner, patented August 14, 1917. The circuit of relay 234 may be traced in part from battery, lower left winding of 15 repeating coil 265, upper right contact of cam 213, winding of relay 234, ring contacts of jack 290 and plug 103, lower alternate contacts of key 108, ring contacts of plug 104 and the jack of test box 101, through the 20 apparatus and circuits of the test box, and returning over the tip contacts of the test box jack and plug 104, upper alternate contacts of key 108, tip contacts of plug 103 and jack 290, lower right contact of cam 212 to 25 ground through the upper left winding of repeating coil 265.

When these tests have been completed, keys 108 and 105 are released, the release of key 105 simulating the release of the connection by the hanging up of the calling subscriber's receiver. Supervisory relay 234 deenergizes opening the holding circuit of relay 227 and that relay deenergizes to advance sequence switch 200 into position 16. 30 The release of relay 227 opens one locking circuit of relay 226 but that relay is maintained energized by way of the lower left contact of cam 203 and the sleeves of jack 290 and plug 103, the inner left contact of relay 110 to ground through resistance 106. In position 16 relay 228 is energized and advances the sequence switch into position 17. In position 17 a sender is again associated with the district selector 250 and the operation 35 of the monitor time measuring switch M is again initiated by the operation of relay 626. When switch M reaches position 5 relays 1212, 1215, 1229 and 1200 have been operated and the circuit is closed for applying coin collection current from the source 1261 of positive current through the inner right contact of relay 1229, winding of relay 1243, inner left front contact of coin collection relay 1212, outer right front contact 40 of relay 1215, thence in parallel through bank terminals 1248 and 1249, wipers 1206 and 1233, outer right front contact and outer left front contact of relay 1200, outer right back contact and outer left back contact of relay 1201, thence over conductors 1202 and 1203 and over the circuit previously traced to the tip and ring contacts of plug 103 and to ground through the winding of relay 111. Current now flowing through relay 111 is 45 sufficient to operate that relay. The opera-

tion of relay 111 opens the locking circuit of relay 110 and that relay deenergizes extinguishing lamp 112 and removing ground at its contact from the sleeve of plug 103 and jack 290. As long as coin collection current 50 flows, relay 110 remains locked at its front contact but releases when the current ceases to flow. The removal of ground from the sleeve of plug 103 permits relay 226 to de- 55 energize, disconnecting the sender and releasing relay 626 to restore switch M and the rest of the sender. The deenergization of relay 226 advances sequence switch 200 to position 18 in which position the district selector switch is restored to normal, where- 60 upon sequence switch 200 is returned to position 1. Since tests have now been completed on selector 250, plug 103 will be removed from jack 290 and inserted in the corresponding jack of some other district 65 selector. The removal of plug 103 from jack 290 removes ground from the holding lead 291, making district selector 250 again selectable to line switches.

What is claimed is:

1. In a telephone exchange system, a trunk circuit, an auxiliary switch, a relay, means for connecting said relay to said trunk circuit in certain positions of said auxiliary switch, means for arresting said auxiliary switch in a position prior to the positions in which said relay is connected to said trunk circuit, means normally controlled by the deposit of a coin for disabling said arresting means, a test line, and means in said test line for simulating the deposit of a coin to operate said disabling means to bring about the connection of said relay to said trunk circuit.

2. In a telephone exchange system, a trunk circuit, an auxiliary switch, a relay, means for connecting said relay to said trunk circuit in certain positions of said auxiliary switch, means for arresting said auxiliary switch in a position prior to the positions in which said relay is connected to said trunk circuit, means normally controlled by the deposit of a coin for disabling said arresting means, a test line, and means in said test line for simulating the deposit of a coin to operate said disabling means to bring about the connection of said relay to said trunk circuit.

3. In a telephone exchange system, a trunk circuit, an auxiliary switch, a relay, means for connecting said relay to said trunk circuit in certain positions of said auxiliary switch, means for arresting said auxiliary switch in a position prior to the positions in which said relay is connected to said trunk circuit, means normally controlled by the deposit of a coin for disabling said arresting means, a test line, and operator controlled means in said test line for simulating the deposit of a coin to operate said disabling means to bring about the connection of said relay to said trunk circuit.

4. In a telephone exchange system, a trunk circuit, an auxiliary switch, a relay, means for connecting said relay to said trunk circuit in certain positions of said auxiliary switch, means for arresting said auxiliary switch in a position prior to the positions in which said relay is connected to said trunk circuit, means normally controlled by the deposit of a coin for disabling said arresting means, a test line, and operator controlled means in said test line comprising a key and a relay controlled thereby

for simulating the deposit of a coin to operate said disabling means to bring about the connection of said first mentioned relay to said trunk circuit.

5. In a telephone exchange system, a trunk circuit, an auxiliary switch, a relay, means for connecting said relay to said trunk circuit in certain positions of said auxiliary switch, means for arresting said auxiliary switch in a position prior to the positions in which said relay is connected to said trunk circuit, a circuit normally adapted to be closed to ground through a coin for disabling said arresting means, a test line, and means in said test line for closing said circuit to ground to operate said disabling means to bring about the connection of said relay to said trunk circuit.

5. In a telephone exchange system, a trunk circuit, an auxiliary switch, a relay, means for connecting said relay to said trunk circuit in certain positions of said auxiliary switch, means for arresting said auxiliary switch in a position prior to the positions in which said relay is connected to said trunk circuit, means normally controlled by the deposit of a coin for disabling said arresting means, a test line, operator controlled means in said test line comprising a key and a relay controlled thereby for simulating the deposit of a coin to operate said disabling means to bring about the connection of said first mentioned relay to said trunk circuit, a source of coin collect current, and means for releasing said second mentioned relay in response to the application of said coin collect current to the trunk circuit.

6. In a telephone exchange system, a trunk

6. In a telephone exchange system, a trunk

circuit, an auxiliary switch, a relay, means for connecting said relay to said trunk circuit in certain positions of said auxiliary switch, means for arresting said auxiliary switch in a position prior to the positions in which said relay is connected to said trunk circuit, means normally controlled by the deposit of a coin for disabling said arresting means, a test line, operator controlled means in said test line comprising a key and a relay controlled thereby for simulating the deposit of a coin to operate said disabling means to bring about the connection of said first mentioned relay to trunk circuit, a source of coin collect current, means for releasing said second-mentioned relay in response to the application of said coin collect current to the trunk circuit, and a signal displayed as long as said coin simulating means is operated.

7. In a telephone exchange system, a trunk circuit, an auxiliary switch, a relay, means for connecting said relay to said trunk circuit in certain positions of said auxiliary switch, means for arresting said auxiliary switch in a position prior to the positions in which said relay is connected to said trunk circuit, means normally controlled by the deposit of a coin for disabling said arresting means, a test line, a test box, means in said line for simulating the deposit of a coin to operate said disabling means to bring about the connection of said relay to said trunk circuit, and means in said test line for connecting said trunk circuit to said test box. 70

In witness whereof, I hereunto subscribe my name this 19th day of November, A. D., 1923.

JOHN B. RETALLACK.
